(57) **CLAIM**

(21) Appl. No.: **29/295,893**

The ornamental design for a front bezel for computer enclosure, as shown and described.

(22) Filed: **Oct. 10, 2007**

DESCRIPTION

(30) **Foreign Application Priority Data**

May 11, 2007 (CN) 2007 3 0200339

FIG. 1 is a perspective view of a front bezel for computer enclosure showing our new design;

(51) **LOC (8) Cl.** **14-02**

FIG. 2 is a front elevational view thereof;

(52) **U.S. Cl.** **D14/444**

FIG. 3 is a left-side, elevational view thereof;

(58) **Field of Classification Search** D14/441–446,

FIG. 4 is a right-side, elevational view thereof;

D14/308; D13/162, 184, 199; 312/223.2,

FIG. 5 is a top plan view thereof;

312/326; 361/680–686, 690–696; 369/14,

FIG. 6 is a bottom plan view thereof; and,

369/34.01, 36.01

FIG. 7 is a perspective view of the front bezel being mounted to a computer enclosure.

See application file for complete search history.

The broken lines are for illustrative purposes only and form no part of the claimed design.
